UNITED STATES PATENT OFFICE.

GEORGE ALFRED BRYAN, OF PERU, INDIANA, ASSIGNEE TO BRYAN HARVESTER COMPANY, INC., A CORPORATION OF NEW MEXICO.

STEAM GENERATOR.

Application filed March 9, 1922. Serial No. 542,204.

My invention relates to steam generators or boilers and, more particularly, to portable steam generators such as are used on steam tractors, trucks and other self-propelled vehicles, in which a liquid fuel is employed. In some aspects of my invention, it is chiefly applicable to steam generators of the type shown in my copending application, Serial No. 490,354, filed August 6, 1921. That type 5 of steam generator consists essentially of two bottom or base headers provided at their ends with upstanding water legs which communicate at the top with intermediate steam separating drums, and a dry steam drum 10 communicating with both of the intermediate separating drums. Water tubes join each header with the respective intermediate drum, and these tubes are bent to run back and forth across the generator, the tubes of 15 the two sets alternating with each other and being nested very closely together. A suitable source of heat, such as a liquid fuel burner, is provided underneath the water tubes. The water level is normally within 20 the separating drums.

It is common with steam generators of this type to dispose the superheating and fuel vaporizing coils in the fire pan directly over the burners. Due to the extreme heat 25 to which they are subjected in that location, it is necessary to make them of some special metal, such as nichrome, and practice has demonstrated that even though such expensive metals are employed, these coils burn 30 out with comparative frequency. In order to renew them when such an accident occurs, it is necessary to take off the fire pan with its inclosed burner construction to afford access to the coils.

40 A general object of my invention is to obviate the disadvantages above referred to. Various other objects and advantages of my invention will appear from the description hereinafter of the construction chosen 45 for the purpose of illustration.

To render the superheating and fuel vaporizing coils more easily accessible and also to permit of the employment of a cheaper metal in their composition, I propose to take 50 these coils out of the fire pan and support them on the water tubes, preferably the lowermost bend thereof, immediately above the burners. If necessary an additional turn for each coil may be employed in order to 55 obtain the same capacity. In order to make

these heating coils readily accessible and in order that they may not interfere with the removal of the water tubes, the bends of the water tubes upon which the coils are supported, are shortened, so as not to overlap. 60

My invention also includes various other features of construction, and details and arrangement of parts, as will hereinafter more fully appear. I shall now describe the illustrated embodiment of my invention and shall 65 thereafter point out my invention in claims.

Figure 1 is a more or less conventional representation in plan of a steam tractor embodying my invention;

Figure 2 is a rear end elevation of the 70 boiler or steam generator and associated parts with the frame and jacket in section;

Figure 3 is a horizontal section of the generator on line 3-3 of Figure 2;

Figure 4 is a detail, partially in section, 75 of my improved fuel vaporizing coil.

Referring to Figure 1, it will be seen that the boiler, indicated generally by the reference character 1, is situated at the front end of the tractor frame, and that the transmission gear case 2 is situated on the rear axle along with the differential, while between the boiler and the transmission case is the steam engine, indicated generally by the reference character 3. The boiler, which 80 is enclosed within the jacket 4, has two U-shaped side members 5 and 6, constituting a base header and two upstanding water legs, and two intermediate separating drums 7 and 8 with which the top ends of the two 85 side members, respectively, communicate, and a dry steam drum 9 communicating with the two intermediate drums 7 and 8. Two sets of water tubes, 10 and 11, connect the base headers of the side members 5 and 6 90 with the intermediate drums 7 and 8, respectively. These water tubes are bent upon themselves to run back and forth across the generator, except the lower bends thereof, which extend only half way across, so as not 95 to overlap, as indicated in Figure 2.

Within the intermediate drums 7 and 8 and near the top thereof, are supported longitudinally extending baffle plates 12 and 13, respectively, and the upper ends of the 100 water tubes 10 and 11 are extended up into the intermediate drums close to the under side of the baffle plates 12 and 13, as shown. The communicating pipes between the dry 105 steam drum 9 and the intermediate drums 7 110

and 8 enter the top of the intermediate drums, so that the baffle plates are disposed between the outlet ends of the two water tubes 10 and 11 and the openings to the pipes leading to the steam drum 9. In this way, the mingled water and steam from the pipes 10 and 11 are caused to strike the baffle plates and the water returns by gravity while the steam rises from the more or less quiescent water in the drums 7 and 8, and passes over into the drum 9 with a minimum of priming. The water in the entire system is thereby kept steadier and consequently the reading in the water level indicator is more constant.

Underneath the boiler is a fire pan 14 in which are the burners 15 of usual construction for vaporized liquid fuel. Supported upon the bottom short bend of the water tubes 11, is the vaporizer coil 16, while the super-heating coils 17 for the same are disposed upon the bottom short bend of the water tubes 10. Steam is taken off from the steam drum 9 at an outlet 9^a in its rear end through pipe 18, whence it passes to the throttle 19 and from thence to a suitable governor 20, and from thence through pipe 21 to the superheater 17. From the superheater it passes through pipe 22 to the valve chamber of the engine 3. The superheater coil is shown as made in a series of as many hair-pin bends as are necessary, the bends being substantially the full length of the boiler. In this way the superheater is supported throughout its length down close to the fire and yet is not within the flame. It is, therefore, less liable to burn through.

The vaporizer coil 16 is of a similar shape to the superheater coils, one end being connected to the inlet pipe 23 for the fuel, which leads from a suitable pump (not shown) in the usual way, and the other end is connected by a pipe 24 to an automatic cut-off 25. A pipe 26 which connects with the outlet end of the automatic cut-off 25, terminates in a jet directed into the usual air mixing chamber from whence it is led through branch pipes, as shown, underneath the burner 15.

In addition to the fact that the vaporizer and superheating coils are supported outside of the flames, although in the region of relatively great heat, an advantage of this supporting construction is the ready accessibility of these coils. If one of the coils burns out, it is only necessary to open the door of the jacket 4 on that side, uncouple the connections at the ends of the coil, remove the coil and replace it with a new one. Also, if occasion arises to remove one of the water tubes, it is only necessary to remove the heating coil supported by the tubes on that side before uncoupling the water tube and removing it. Due to the fact that the bends on which the heating coils are supported do not overlap, the heating coil sup-

ported on the other side of the boiler does not interfere with the removal of the water tube.

The vaporizer coil 16 is shown in detail in Figure 4. In each straight length an individual cable 27 of twisted wire is provided. To permit the ready insertion and removal of these cables, an opening 28 is provided at each bend, so arranged that cable 27 of either leg may be withdrawn or inserted through this opening. These openings 28 are closed with suitable screw plugs 29.

It is obvious that various modifications may be made in the construction shown in the drawings and above particularly described within the principle and scope of my invention.

I claim:

1. In a steam generator, a water circulating system including two base headers and for each base header a superposed steam separating drum, and two sets of water tubes joining the respective headers with the superposed steam separating drums, the water tubes being bent upon themselves to run back and forth across the generator and the bends of the two sets in one plane being shortened so as not to overlap.

2. In a steam generator, a water circulating system including two base headers and for each base header a superposed steam separating drum, two sets of water tubes joining the respective headers with the superposed steam separating drums, the water tubes being bent upon themselves to run back and forth across the generator and the bends of the two sets in one plane being shortened so as not to overlap, a heating coil supported in the said shortened bends of one of the sets of water tubes, and a source of heat underneath the generator.

3. In a steam generator, a water circulating system including two base headers, two superposed steam separating drums, two sets of water tubes joining each header with its respective drum, the water tubes being bent upon themselves to run back and forth across the generator and having their lowermost bends shortened so as not to overlap, a steam superheating coil disposed in the said shortened bends of one set of water tubes, and a source of heat underneath the generator.

4. In a steam generator, a water circulating system including two base headers, two superposed steam separating drums, two sets of water tubes joining each header with its respective drum, the water tubes being bent upon themselves to run back and forth across the generator and having their lowermost bends shortened so as not to overlap, a steam superheating coil disposed in the said shortened bends of one set of water tubes, a fuel vaporizing coil disposed in the

said shortened bends of the other set of water tubes, and a source of heat underneath the generator.

5. In a steam generator, a water circulating system including two base headers and two sets of water tubes communicating at their lower ends with the respective headers and bent upon themselves to run back and forth across the generator, the bends of the 10 two sets in one plane being shortened so as not to overlap, a steam drum in communication with the upper ends of the water tubes, a steam superheating coil communicating with the steam drum and disposed in the said 15 shortened bends of one set of water tubes, a liquid fuel burner underneath the generator, and a fuel vaporizing coil communicating with the burner and disposed in the said shortened bends of the other set of water tubes.

16. In the said shortened bends of one set of water tubes, and a source of heat underneath the generator.

6. In a steam generator, a water circulating system including two base headers and

two sets of water tubes communicating at 20 the lower ends to the respective headers and bent upon themselves to run back and forth across the generator, the bends of the two sets in one plane being shortened so as not to overlap, a steam drum in communication 25 with the upper ends of the water tubes, a steam superheating coil communicating with the steam drum and disposed in the said shortened bends of one set of water tubes, a liquid fuel burner underneath the generator, and a fuel vaporizing coil communicating 30 with the burner and disposed in the said shortened bends of the other set of water tubes.

In witness whereof, I hereunto subscribe 35 my signature.

GEORGE ALFRED BRYAN.
